[57] **CLAIM**

The ornamental design for a ladder cap, as shown and described.

DESCRIPTION

FIG. 1 is a perspective view of a ladder cap showing my new design, the broken lines are for illustrative purposes only and form no part of the claimed design;
FIG. 2 is a back elevational view thereof;
FIG. 3 is a front elevational view thereof;
FIG. 4 is a top plan view thereof;
FIG. 5 is a bottom plan view thereof; and,
FIG. 6 is a side elevational view thereof, the opposite side elevational view being a mirror image of that shown.
